CANOPY FOR A PICKUP TRUCK BED

William C. Robertson, P.O. Box 338,
Stroud, Okla. 74079

Filed Mar. 25, 1974, Ser. No. 454,267

Term of patent 14 years

Int. Cl. D12—16

U.S. Cl. D12—156

FIG. 1

FIG. 2

FIG. 3

FIG. 4

FIG. 5

FIG. 1 is a rear perspective view of a canopy for a pickup truck bed showing my new design;

FIG. 2 is a top plan view thereof;

FIG. 3 is a side elevational view thereof, it being understood that the opposite side is a mirror image of the side shown herein;

FIG. 4 is a rear elevational view thereof; and

FIG. 5 is a front elevational view thereof.

I claim:

The ornamental design for a canopy for a pickup truck bed, as shown and described.
